UNITED STATES PATENT OFFICE.

CHARLES G. WILLSON, OF READING, PENNSYLVANIA.

DESIGN FOR A BADGE.

SPECIFICATION forming part of Design No. 22,659, dated August 1, 1893.

Application filed April 14, 1893. Serial No. 470,382. Term of patent 14 years.

To all whom it may concern:

Be it known that I, CHARLES G. WILLSON, a citizen of the United States, residing at Reading, in the county of Berks, State of Pennsylvania, have invented and produced a new and original Design for a Badge, of which the following is a specification, reference being had to the accompanying drawings, forming part thereof.

10 The leading feature of my design for a badge is a two-faced watch above a forked head which carries an elk's tooth projecting from its lower extremity, and an elk's head resting upon the obverse and having its antlers resting about the periphery of the watch, and visible at both faces of the badge.

15 Figure 1 represents the obverse of a design for a badge embodying my design. Fig. 2 represents the reverse thereof, these two views being deemed necessary to fully illustrate my design.

20 In the drawings: A designates an elk's tooth, on the obverse of which is the seal B. C designates a forked head at the top of the

tooth A, and D designates a two-faced watch 25 on said head.

E designates an elk's head on the seal B, whose antlers F embrace the periphery of the watch D.

G designates a scroll on the top of the 30 head C.

On the dial of the watch D are forget-me-nots H. On the reverse appear the tooth A, head C, the two-faced watch D, and portions of the antlers F.

35 On the dial of the watch are two drinking glasses J.

What I claim is—

1. In the design for a badge, the obverse, substantially as shown and described. 40
2. In the design for a badge, the reverse, substantially as shown and described.
3. The design for a badge substantially as shown and described.

CHAS. G. WILLSON.
